Primary Examiner — Marie D. Fast Horse*(74) Attorney, Agent, or Firm* — Kelley Drye & Warren LLP(57) **CLAIM**

The ornamental design for a point of sale device as shown and described.

DESCRIPTION

FIG. 1 is a top perspective view of a point of sale device showing our new design;

FIG. 2 is a bottom perspective view thereof;

FIG. 3 is a front elevational view thereof;

FIG. 4 is a rear elevational view thereof;

FIG. 5 is a left elevational view thereof;

FIG. 6 is a right elevational view thereof;

FIG. 7 is a top plan view thereof;

FIG. 8 is a bottom plan view thereof;

FIG. 9 is an exploded view of the point of sale device of FIG. 1; and,

FIG. 10 is a top perspective view of the point of sale device of FIG. 1, shown in a partially opened state for use.

The broken lines depict portions of the point of sale device that form no part of the claimed design.
